UNITED STATES PATENT OFFICE.

ROBERT G. SAVILL, OF PHILADELPHIA, PENNSYLVANIA, ASSIGNOR TO THOMAS M. SAVILL, ROBERT G. SAVILL, AND WILLIAM S. SAVILL, ALL OF PHILADELPHIA, PENNSYLVANIA, COPARTNERS TRADING AS THOMAS SAVILL'S SONS, OF PHILADELPHIA, PENNSYLVANIA.

DESIGN FOR A FAUCET.

48,832.

Specification for Design.

Patented Apr. 4, 1916.

Application filed May 29, 1915. Serial No. 31,302. Term of patent 14 years.

To all whom it may concern:

Be it known that I, ROBERT G. SAVILL, a citizen of the United States, and a resident of Philadelphia, county of Philadelphia, State of Pennsylvania, have invented a new, original, and ornamental Design for Faucets, which is shown in the accompanying drawings, in which—

Figure 1 is a plan view, and Fig. 2 a side elevation of a faucet embodying the design.

I claim:

The ornamental design for a faucet substantially as shown.

ROBERT G. SAVILL.

Witnesses:

CHARLES E. KLINE,
W.M. C. SAVILL.
